PLLC; Aaron R. Cramer

(57) **CLAIM**

The ornamental design for a rafter installation tool, as shown and described.

DESCRIPTION

FIG. 1 is a perspective top front right view of a rafter installation tool, showing my new design;

FIG. 2 is a front elevation view thereof, with the rear elevation view being identical;

FIG. 3 is the right elevation view thereof, with the left elevation view being identical;

FIG. 4 is a top plan view thereof; and,

FIG. 5 is a bottom plan view thereof.
